UNITED STATES PATENT OFFICE.

HAZELLE R. CHRISTIANSEN, OF ROCKFORD, ILLINOIS.

PENCIL.

Application filed August 14, 1922. Serial No. 581,570.

To all whom it may concern:

Be it known that I, HAZELLE R. CHRISTIANSEN, a citizen of the United States, and a resident of the city of Rockford, county of 5 Winnebago, and State of Illinois, have invented certain new and useful Improvements in Pencils, of which the following is a specification.

My invention relates to improvements in 10 lead pencils of the type adapted to contain a plurality of small leads and utilizing said leads by feeding the same through one end of the pencil for use, the object of the invention being to provide a construction of 15 this character by means of which the leads may be readily transferred for use when one is consumed.

Other objects will appear hereinafter.

The invention consists in the combinations and arrangements of parts hereinafter described and claimed.

The invention will be best understood by reference to the accompanying drawings forming a part of this specification, and in 25 which,

Fig. 1 is a view shown partially in longitudinal section of a pencil embodying the invention,

Fig. 2 is an enlarged section taken on line 30 2-2 of Fig. 1,

Fig. 3 is an enlarged section taken on line 3-3 of Fig. 2, and

Fig. 4 is a perspective view of a closure plate employed in the construction.

The preferred form of construction as illustrated in the drawings, comprises a hollow barrel or casing 5 having a lead channel 6 leading from the interior thereof through one end, the inner end of the channel 6 being flared at 7 to facilitate the passage of a lead thereinto. A rotatable lead container 8 is mounted in the barrel 5 and is provided with a plurality of peripheral pockets 9 open at both ends and adapted and arranged to contain the individual leads 10 as indicated. Arranged at the inner end of the container 8 is a closure plate 11 provided with lugs 12 engaging notches 13 in the inner walls of the barrel and preventing turning or rotating of said plate. The plate 11 is provided with a segmental notch 14 adapted to be brought into registration with the respective pockets 9 so as to permit the passage of the leads therefrom into the channel 6-7. By this arrangement it will be observed that by turning the container

8 in the barrel 5, the different lead pockets 9 may be brought successively into registration with the notch 14 and the various leads delivered therefrom into the channel 6-7. 60

The lead container 8 is given a snug frictional fit in the barrel 5 and is provided at its outer end with a knurled flange 15 facilitating manipulations thereof. On its underside the flange 15 is provided with a plurality of lugs 16 adapted to engage notches 17 in the corresponding end of barrel 5 and whereby the container 8 will be locked in its various positions of adjustments. By this arrangement it will be observed by pulling outwardly on flange 15, the lugs 16 may be readily disengaged from the notches 17 and the container 8 adjusted to permit the discharge of a fresh lead into the channel 6-7. 75

A hollow stem 18 is given a frictional fit in the lead container 8 and provided at its outer end with a head 19. The head 19 is provided with an eraser 20 and a threaded closure cap 21 as shown. The stem 18 is provided with a central oblong bore 22 and a threaded stem 23 is arranged to operate in said bore, said stem 23 being provided with an oblong head 24 fitting the bore 22 and whereby longitudinal movement 85 of the stem 23 is permitted but rotation thereof relatively to the stem 18 is prevented. The stem 23 is threaded in the inner end of the pencil container 8 and is provided with a flat head 25 for contact with the inner ends of the leads 10 for feeding the same in use. By this arrangement when a fresh lead has been discharged into the channel 6-7 from the container 8, said lead may be readily fed through the channel 6 for use by simply turning the cap 21. When the lead is consumed, the stem 23 is retracted by turning the cap 21 in the reverse direction, whereupon a fresh lead is delivered into the channel 6-7 and the cap 100 21 manipulated to cause feeding of said fresh lead for use as explained above. In this way the different leads in the container 8 may be readily transferred from the container into the channel 6 for use without 105 removing or disturbing any of the parts of the pencil. When it is desired to provide a fresh supply of leads, the stem 18 is simply withdrawn from the container sufficiently to permit the insertion of said leads 110 in the pockets 9 when the stem 18 is restored to original position and the pencil

used until all of said leads are consumed. The specific form and arrangement of parts is a simple and effective one for the purpose.

5 While I have illustrated and described the preferred form of construction for carrying my invention into effect, this is capable of variation and modification without departing from the spirit of the invention. I, 10 therefore, do not wish to be limited to the precise details of construction set forth, but desire to avail myself of such variations and modifications as come within the scope of the appended claims.

15 Having described my invention, what I claim as new and desire to secure by Letters Patent is:

1. A pencil comprising a hollow barrel having one end formed into a lead channel 20 opening through the corresponding end thereof; a rotatable lead container in said body, said lead container being provided with a plurality of lead pockets; a sealing plate in said barrel at the inner end of said 25 container, there being a notch in said sealing plate adapted to register with the respective pockets in said lead container upon rotation thereof; and means for feeding a lead through said lead channel, substantially 30 as described.

2. A pencil comprising a hollow barrel having one end formed into a lead channel opening through the corresponding end thereof; a rotatable lead container in said 35 body, said lead container being provided with a plurality of lead pockets; a sealing plate in said barrel at the inner end of said container, there being a notch in said sealing plate adapted to register with the 40 respective pockets in said lead container upon rotation thereof; a rotatable stem in said lead container and operating to feed a lead through said channel; and means for operating said stem to feed a lead through 45 said lead channel, substantially as described.

3. A pencil comprising a hollow barrel having one end formed into a lead channel opening through the corresponding end thereof; a rotatable lead container in said 50 body, said lead container being provided with a plurality of lead pockets; a sealing plate in said barrel at the inner end of said container, there being a notch in said sealing plate adapted to register with the 55 respective pockets in said lead container upon rotation thereof; a rotatable stem in said lead container and operating to feed a lead

through said channel; a second stem operating longitudinally in said first stem and threaded in said lead container, substantially as described.

4. A pencil comprising a hollow barrel having one end formed into a lead channel opening through the corresponding end thereof; a rotatable lead container in said 65 body said lead container being provided with a plurality of lead pockets open at both ends; a sealing plate in said barrel at the inner end of said container, there being a notch in said sealing plate adapted to 70 register with the respective pockets in said lead container upon rotation thereof; a rotatable stem in said lead container, said stem being provided with an oblong bore; and a second stem operating in said oblong 75 bore and having an oblong head at its outer end preventing rotation in said bore, the inner end of said inner stem being threaded in said hollow stem, substantially as described.

5. A pencil comprising a hollow barrel having one end formed into a lead channel opening through the corresponding end thereof, the opposite end of said barrel being notched; a rotatable lead container in said 80 body, said lead container being provided in its periphery with a plurality of lead pockets open at both ends; a flange on said lead container provided with lugs adapted to fit the notches in said barrel; a sealing 85 plate in said barrel at the inner end of said container, there being a notch in said sealing plate adapted to register with the respective pockets in said lead container upon rotation thereof; lugs on the sealing plate, 90 there being notches in the inner walls of the barrel to receive said lugs and prevent turning of said sealing plate; a rotatable stem in said lead container, said stem being provided with an oblong bore; and a second 95 stem operating in said oblong bore and having an oblong head at its outer end preventing rotation in said bore, the inner end of said inner stem being threaded in the inner end of said lead container, substantially as 100 described.

In testimony whereof I have signed my name to this specification in the presence of two subscribing witnesses.

HAZELLE R. CHRISTIANSEN.
